MONOGRAMS OR THE LIKE

Salvador Reynoso, Chicago, Ill.

Application October 5, 1946, Serial No. 133,794

Term of patent 3½ years

(Cl. D64—12)

To all whom it may concern:

Be it known that I, Salvador Reynoso, a citizen of the United States of America, residing at Chicago, in the county of Cook and State of Illinois, have invented a new, original, and ornamental Design for an Alphabet for Forming Monograms or the Like, of which the following is a specification: reference being had to the accompanying drawing, forming part thereof.

The drawing illustrates face views of an alphabet for forming monograms or the like, showing my new design.

I claim:

The ornamental design for an alphabet for forming monograms or the like, as shown.

SALVADOR REYNOSO.
